UNITED STATES PATENT OFFICE.

SADIE E. BURKE, OF BETHLEHEM, PENNSYLVANIA.

LINGERIE CLASP.

Application filed March 23, 1929. Serial No. 349,415.

The present invention relates to lingerie clasps of a type adapted for retaining the lingerie shoulder straps in a predetermined position upon the shoulders of the wearer so as to prevent the slipping of the straps from the shoulders.

One of the principal objects of the invention is to provide a neat and attractive device of this character which may be secured to the inner side of the outer garment at a point adjacent the shoulder seam and having means for engaging the lingerie shoulder straps so as to prevent slipping of the straps from the shoulder but at the same time permits freedom of movement of the straps in a longitudinal direction so as to prevent a binding action or strain upon the straps during the normal movement of the body and arms of the wearer.

A still further object is to provide a device of this character which is free from any discomforts and which permits the releasing of the lingerie shoulder straps for removing the garments when desired.

Other objects and advantages reside in the special construction, combination and arrangement of the various elements forming the invention, as more fully hereinafter described and claimed, reference being had to the accompanying drawing forming part hereof, wherein like numerals refer to like parts throughout the specification and in which—

Figure 1 is a perspective view of the device showing the relative position of the same when in use,

Figure 2 is a plan view, and

Figure 3 is an edge elevational view with the separable fastener shown in open position.

Referring now to the drawing in detail, wherein for the purpose of illustration I have disclosed a preferred embodiment of the invention, the numeral 5 designates an attaching plate which may be of any desired formation and preferably constructed of relatively thin sheet material, the present embodiment disclosing a plate of square shaped formation having perforations 6 formed therein adjacent two of its opposite corners and having the ends of a pair of chains or other flexible members suitably secured to openings formed at the other corners of the plate. One of the chains extends unbroken for attaching to the other of

the plates and the other of said chains is composed of a pair of sections 8 each attached at one end to the respective plates and having their free ends adapted for connection by a snap fastener 9 or other suitable separable fastening device.

The plates 5 are adapted for attaching at the inner side of an outer garment 10 adjacent the shoulder seam thereof by sewing, the thread being inserted through the perforations 6 of the plates. The chains are disposed parallel with the shoulder seam of the garment as more clearly illustrated in Figure 1 of the drawing and arranged with the lingerie shoulder strap 11 of the under garment of the wearer disposed over the chain having a fastener provided therein and under the unbroken chain. When arranged in the manner indicated it will be apparent that the shoulder strap will be prevented from sliding over the shoulder of the wearer but at the same time the strap may slide freely between the parallel sections of the chains in a longitudinal direction so as not to interfere with the freedom of the movements of the person.

The plates 5 may be constructed of any suitable material and ornamented in any desired manner and the plates may also be connected by any flexible member such as ribbon or the like in lieu of the chains.

It is obvious that the invention is susceptible of various changes and modifications without departing from the spirit thereof or the scope of the appended claims and I accordingly claim as my own all such forms of the invention to which I am entitled.

I claim:

1. A lingerie strap holder of the class described comprising a pair of garment attaching plates adapted for securing to the under side of the garment adjacent the shoulder seam thereof and a pair of flexible members connecting said plates in parallel relation with the lingerie strap positioned between said members, one of said flexible members being composed of a pair of detachable sections and a separable fastener connecting the free ends of said sections to each other.

2. A lingerie strap holder of the class described comprising a pair of garment attaching plates having perforations formed therein for the insertion of thread for attaching to the garment, a pair of flexible

members having their ends attached at the opposite sides of said plates and disposed in spaced parallel relation, one of said members being unbroken and the other of said members being composed of a pair of sections having their free ends adapted for detachably connecting to each other whereby to

position the flexible members at opposite sides of the lingerie strap for retaining the same in position upon the shoulder of the ¹⁰ wearer and providing for the free movement of the strap in a longitudinal direction.

In testimony whereof I affix my signature.

MRS. SADIE E. BURKE.
